UNITED STATES PATENT OFFICE.

GEORGE R. ADAMS, OF HIAWATHA, KANSAS, ASSIGNOR TO MILTON O. ADAMS, OF KANSAS CITY, MISSOURI.

WASHING-MACHINE.

No. 923,101.

Specification of Letters Patent.

Patented May 25, 1909.

Application filed August 8, 1908. Serial No. 446,550.

To all whom it may concern:

Be it known that I, GEORGE R. ADAMS, a citizen of the United States, residing at Hia-watha, in the county of Brown and State of 5 Kansas, have invented certain new and useful Improvements in Washing-Machines, of which the following is a specification.

The object of this invention, generally stated, is to improve the construction of the 10 washing machine illustrated and described in my prior patent No. 864,591, dated August 27, 1907. In said patent the agitator comprises a pair of crossed bars, preferably of wood, said bars being provided with clothes- 15 engaging clips, the shanks of which are driven into the lower sides of said bars.

The object of the present invention is to brace said agitator bars and to provide improved means for supporting the clothes- 20 engaging members in order to obviate the necessity for driving them into said bars and thereby weakening the latter.

In the accompanying drawings, Figure 1 is a vertical central section through a washing 25 machine embodying the features of my invention. Fig. 2 is a perspective view of the brace for the agitator, this view also illustrating the improved means for attaching the clothes-engaging clips. Fig. 3 is a sectional 30 view and Fig. 4 is a perspective view illustrating the improved bracket or support for the tub. Fig. 5 is a detail view of a tub-retaining strap.

The embodiment selected for illustration 35 comprises a stand 1, which may consist of four legs 2, suitably braced and united by cross-bars 3, the legs and cross-bars preferably being connected by means of rivets or welding, in order to obviate the use of bolts 40 and nuts. The legs 2 preferably are of angle iron. The tub 4 may be rectangular in horizontal cross-section, as indicated. It is herein shown as supported upon the stand by means of brackets 5 (shown in detail in Fig. 4). 45 Preferably the brackets are formed integral with the legs 2; each bracket may consist of two triangular lugs 6, each struck up from one web of the leg to lie in the same or substantially the same horizontal plane. The 50 portion of each leg over the bracket 5 is bent

out of alinement with the rest of the leg to conform to the tub 4.

In order to prevent the tub from being displaced when the machine is operated violently or irregularly, or from other causes, I 55 provide straps 7 at the corners of said tub, said straps embracing the upper ends of the legs 2 of the stand 1. The tub may be removed from the stand by lifting it off said stand. 60

The agitator comprises two crossed bars 8, preferably of wood. To strengthen said bars, I provide a brace 9, the construction of which may be as shown in Fig. 2. As there-in shown, the brace consists of a cruciform member having flanges 10 at its edges to lie at the sides of the bars 8, and a central hub 11 to extend within an opening 12 in the agitator. The brace 9 is connected with the bars 8 by means of studs 13 on said brace extending into openings in the under side of said bars. Upon the under side of the brace 9 are clothes-engaging loops 14. Preferably 65 the brace 9, with its hub 11, studs 13 and loops 14, is an integral casting. The agitator 70 is secured to the lower end of a vertical operating shaft 15, which passes through the hub 11, a bolt 16 extending through said hub and said shaft and uniting said parts. The shaft 15 is provided with a crank 17. 75

The brace 9, with its marginal edges 10 and studs 13, materially strengthens the agitator to withstand the twisting stresses imposed upon it in use. Said brace also provides a means for attaching the clothes-engaging loops which does not weaken the wood 85 bars 8.

The tub-supporting brackets 5 being integral with the legs 2, are stronger, as well as cheaper, than the cast iron brackets employed in the structure of my said prior patent, and not liable to become detached. 90

I claim as my invention:

1. An agitator for washing machines comprising two crossed bars and a cruciform 95 brace at one side of said bars, said brace having marginal flanges lying at the sides of said bars, said brace having a hub extending into said bars.

2. An agitator for washing machines com- 100

prising two crossed bars and a cruciform brace on the lower side of said bars, said brace having marginal flanges lying at the sides of said bars, a hub extending through 5 said bars, studs extending into said bars, and clothes engaging loops, said brace, marginal flanges, hub, studs and loops being integral.
3. An agitator for washing machines com-

prising a cruciform wooden head, a cruciform metal brace attached to the lower side of 10 said head, and clothes-engaging means on said brace.
